United States Patent Office

Des. 189,385
Patented Nov. 29, 1960

189,385

SHEET DELIVERY APPARATUS

Viktor Schreckengost, Cleveland Heights, Ohio, assignor to Harris-Intertype Corporation, Cleveland, Ohio, a corporation of Delaware

Filed June 30, 1958, Ser. No. 51,612

Term of patent 14 years

(Cl. D64—11)

Fig. 3

Fig. 2

Fig. 1 is a side perspective view of a sheet delivery apparatus showing my new design;

Fig. 2 is another side perspective view thereof, the side opposite thereto being substantially identical in appearance; and

Fig. 3 is a top plan view thereof.

The essential features of the design are included in the portions shown in solid lines on the drawing.

I claim:

The ornamental design for a sheet delivery apparatus, as shown and described.
